DIRK JAN CHRISTIAAN MEYERINGH, OF BROOKLYN, NEW YORK.

OILING SYSTEM FOR STEAM-LINES.

1,294,363.

Specification of Letters Patent.

Patented Feb. 11, 1919.

Application filed March 27, 1918. Serial No. 224,932.

To all whom it may concern:

Be it known that I, DIRK JAN CHRISTIAAN MEYERINGH, a citizen of Holland, and a resident of the borough of Brooklyn, 5 Kings county, city and State of New York, have invented certain new and useful Improvements in Oiling Systems for Steam-Lines, of which the following is a specification.

10 My invention relates to an oiling system for steam lines connected with steam engines and steam devices of various kinds, where it is desired to mix lubricating oil homogeneously with the steam so as to be carried 15 to steam cylinders and other frictionally related parts normally subjected to the action of steam, and thus provide for effective lubrication.

In the prior art, what are known as "Hydrostatic Lubricators" are well known. 20 Here a reservoir or receptacle filled with oil is connected up by two independent pipes to points in the steam line. One of these pipes must, somewhere in its length, reach 25 a higher level than the receptacle, and its terminus is, usually but not necessarily, near the bottom of the receptacle, while the terminus of the other pipe is near the top of the receptacle, a needle valve being placed 30 in such latter pipe just outside the receptacle. The former pipe is termed the "condensation pipe" and the latter pipe the "oil supply pipe." When steam is passing through the steam line a certain percentage 35 thereof condenses in the condensation pipe, thereby providing a hydrostatic head which, after equilibrium is arrived at, presses down into the receptacle, displacing the oil and forcing it past the needle valve and into 40 the steam line as fast as the head is added to by the normal condensation of steam. When a large oil feed is required, the condensation pipe at some point above the reservoir, is often formed as a flat spiral or is 45 globularly expanded in order to afford a greater condensation surface.

In this known form of lubricator the 50 amount of oil fed into the steam line is dependent solely upon the hydrostatic pressure of the condensate in the condensation pipe and this condensate, as is well known, is substantially independent of the volume of steam flowing per unit of time. It fol-

lows, therefore, that if the lubricator be determined so as to provide a suitable supply of oil for a normal steam load, an excess supply of oil will be supplied for a small steam load and a subnormal amount of oil will be supplied for an excess steam load.

It is the object of my invention to provide a lubricator having features of construction similar in many ways to features embodied in hydrostatic lubricators, as just described, but which shall automatically feed an amount of oil into the steam line substantially proportional to the volume of steam flowing through said line in unit time. In this way each unit volume of steam will have exactly the same amount of oil distributed through it at all times whether the steam load be large or small, and the surfaces to be lubricated will, therefore, always receive just the right amount of oil.

Briefly described, my invention comprises 75 an oil reservoir very similar to that used in the known hydrostatic lubricator and somewhat similarly connected by a condensation pipe and needle-valved oil pipe to the steam line. In its preferred form, the 80 points of connection of both pipes to the steam line are substantially at the same level which level is considerably higher than that of the reservoir. Furthermore, the steam pipe, at the point where the oil pipe is connected thereto, is given a decreased cross-section so that the steam velocity at this section is greater than the steam velocity at the section where the condensation pipe is connected. The steam pressure at the point of 90 connection of the condensation pipe will, therefore, be greater than the steam pressure at the point of connection of the oil pipe.

At a suitable distance above the oil receptacle, the condensation pipe is formed as a flat spiral of many convolutions, thus providing a large condensing surface and insuring a constant level for the top of the water column.

The height of the condensation pipe below the spiral, with respect to the height of the oil pipe below its inlet into the steam line, should be inversely as the specific gravities of the water and the oil; in this 105 way the water and oil column will balance

one another and exert no pressure component to force the oil past the needle valve.

Under these circumstances, when steam is flowing through the steam line, the pressure which will be exerted upon the water column in the condensation pipe will be a function of the steam flow in the steam line per unit of time, as will hereinafter appear.

My invention will be better understood by referring to the accompanying figures in which Figure 1 represents a front view of a preferred embodiment of the invention as applied to a steam line; and Fig. 2 represents a plan view thereof.

In the drawings, the oil reservoir, 1, is provided with a cap, 2, for filling, and a valve, 3, for tightly closing the reservoir after it has been filled.

The steam line, 4, is provided with an interposed nozzle section, 5, the cross-section of which, at the ends, is substantially that of the remaining portions of the line, while from the ends to the center the section equally and continuously diminishes.

The condensation pipe 6, enters the nozzle section, 5, at one end, is preferably but not necessarily formed as a spiral of many convolutions at, 7, a little below the level of the nozzle section, and enters the receptacle near the top at 8. Instead of a spiral condenser, as illustrated, I may substitute any other usual form known in the art. And, of course, the condenser may be omitted from its pipe altogether if a certain departure from strict accuracy be considered permissible.

The oil pipe, 9, enters the nozzle section at its center and connects with a sight-feed or drop-counting glass, 10, at its top. The bottom of this feed glass connects with an interior feed pipe 11, which extends upwardly in the receptacle and has its open end just below valve 3. The condensation pipe and the oil pipe are both of comparatively small diameter.

A sight-feed glass, 12, is connected at the top and bottom with the interior of the receptacle and is provided with valves, 13 and 14.

Oil pipe, 9, is provided with a valve, 15, just before it joins sight-feed, 10, and another valve, 16, is interposed between feed pipe, 11, and sight-feed, 10. A needle valve, 17, of usual construction, is located at the bottom of sight-feed, 10, between it and valve, 16.

Valves, 18, and, 19, are provided for condensation pipe and oil pipe, respectively, just before they join the steam line.

Sight-feed 10 is connected by a passage controlled by a valve 20, with a filling cap 21.

Oil pipe, 9, is preferably extended through and beyond the wall of the nozzle section so

as to project into the interior thereof. This prevents oil entering through said oil pipe from flowing over the inner wall of the steam pipe instead of mixing with the steam.

The nozzle section, 5, and spiral, 7, are sufficiently high above the reservoir, 1, to make the dimension W (the height of the water column) be to the dimension H (the height of the oil column), as the specific gravity of the oil is to the specific gravity of the water. In stating these dimensions, it is assumed that the base of the water column, and of the oil column, lies at the constant level of the point of connection of the condensation pipe to the oil reservoir. This is not strictly true but is immaterial since, with a condensation pipe and an oil pipe of reasonable length, vertically, the fluctuating position of the base of the water, and of the oil column, within the limit of the height of the reservoir, will be practically negligible.

To use the apparatus, the same being installed as shown by the drawings, the reservoir, 1, should be filled with oil through the cap, 2, and valve, 3, closed. Valves, 18 and 19, between the condensation and oil pipes and the nozzle section, as also valve, 16, between middle valve, 17, and feed pipe 11, should have been first closed and the remaining valves, 13, 14, and 15 open. Sight-feed, 10, should then be filled with water through cap, 21, and valve, 20, closed. If, now, valves, 16, 18, and 19, be opened and steam turned on, the water pipe, 7, will fill therewith and this steam will gradually condense until the said pipe between the reservoir and spiral, 7, is filled with water.

The velocity of the steam being less at the section passing through valve, 18, than at the section passing through valve, 19, the pressure at this former point will be correspondingly greater. This pressure exerted upon the water column in pipe, 6, will force water drop by drop through outlet, 8, into the receptacle. Water being heavier than oil, each drop of water will displace a drop of oil and oil will therefore be fed, drop by drop through the needle valve into sight-feed, 10, whence it will ascend and fill the oil pipe, 9, and finally enter the nozzle section at its center.

The amount of oil passing into the steam line may be determined by counting the drops which rise, per unit of time, in the sight-feed, 10, and may be regulated by adjusting the needle valve, 17.

As the oil enters into the steam line where the velocity is highest, the certainty of its being thoroughly broken up and mixed with the steam, is a maximum.

That, under the conditions as described, the flow of oil through the needle valve will be substantially proportional to the flow of

steam through the nozzle section, so that each unit volume of steam will contain a unit volume of oil irrespective of the amount of steam passing through the nozzle section in unit time, will appear from the following:

Let

Q =quantity of oil passing through the needle valve per unit of time.

10 p =pressure upon the water column.

p' =pressure upon the oil column.

C' =a constant.

$$(1) \text{ Then } Q = C' \sqrt{(p - p')}$$

15 This is readily deduced from the well known toricellian law covering the discharge of fluids from circular orifices, viz.,

$$(2) Q = Ca \sqrt{2gH} \text{ (See } Kent Mech. Engrs., Pkt-Book, 8th Ed., p. 697.)$$

20 where C and a are constants, H the hydrostatic head, and g the gravitational accelerative constant. In the case now being considered the effective steam pressure $(p - p')$ is the equivalent of H .

25 But the flow of steam, Q' , across a given section of the steam line per unit time, as e. g., past the point of connection of the condensation pipe with the nozzle section, may also be written:

$$(3) Q' = C'' \sqrt{(p - p')}$$

30 C'' being a constant and p and p' having the same meaning as before. (See *Kent Mech. Engrs. Pkt-Book*, 8th ed., p. 592, where the expression is given for the flow of air in pipe.)

$$(4) Q = 0.02871C \sqrt{\frac{pd^5}{L}}$$

40 when C , d^5 and L are constants and p is the pressure difference or, in the present case, the $(p - p')$ of equations (1) and (3).

Hence Q is proportional to Q' , (equation 45), while strictly only applicable to air, is, nevertheless, accurate to within negligible practical limits if applied to steam.)

50 Preferably, that portion of the condensation pipe above spiral, 7, should be insulated in order to be sure that it may always be full of steam and that the top of the water column may be permanently maintained at the level of the spiral. Furthermore, it is important that the spiral should have a sufficiently large surface to insure 55 that, whether the oil consumption be large or small, the temperature of the water passing into the oil receptacle shall remain constant; this is necessary in order that the temperature of the oil itself, and hence the viscosity of the oil, shall remain the same since otherwise an independent effect will be exerted upon the oil consumption.

Instead of connecting the condensation and oil pipes to a nozzle section of the char-

acter described, i. e., instead of having these 65 pipes enter the steam line at points of greater and less cross-section respectively, I may, if I prefer, connect said pipes to a pair of Pitot tubes inserted either in the same cross-section of the steam line or at 70 different points of uniform cross-section, the tube connected with the condensation tube having the plane of its opening across the steam line and the other tube having its opening parallel with the steam line. 75

Where, in the claims, I speak of a "condensation pipe," I mean a pipe adapted to have steam condensed therein so that there will be established, during the operation of the invention, a water column adjacent the 80 "receptacle" and a steam column resting upon the water column with its upper end adjacent the steam line.

Other changes of detail may be made within the spirit and scope of the following 85 claims.

I claim:

1. In an oiling system, in combination with a steam line, a receptacle adapted to contain oil, and a condensation and an oil pipe terminating in said receptacle, the oil pipe in the upper part thereof, the remaining ends of said pipes, respectively, being connected with the steam line at points where the pressures are relatively greater 90 and less. 95

2. In an oiling system, in combination with a steam line, a receptacle adapted to contain oil, and a condensation and an oil pipe terminating in said receptacle, the oil pipe in the upper part thereof, the remaining ends of said pipes, respectively, terminating in the steam line at points of less and greater velocity. 100

3. In an oiling system, in combination with a steam line, a receptacle adapted to contain oil, and a condensation and an oil pipe terminating in said receptacle, the oil pipe in the upper part thereof, the remaining ends of said pipes respectively terminating in the steam line at points of greater 105 and less cross-section. 110

4. In an oiling system, in combination with a steam line, a receptacle adapted to contain oil, a condensation pipe which passes through a region higher than the receptacle, and an oil pipe terminating in said receptacle, the oil pipe in the upper part thereof, the remaining ends terminating in the steam line at points having, respectively, a greater and less cross-section. 115 120

5. An oiling system comprising a receptacle adapted to contain oil, a steam line having a contracted portion, a condensation pipe having a horizontal spiral between its ends, one of which connects to the steam line at a point of relatively large cross-section, while the other end terminates in the receptacle, and an oil pipe, one end of which 125

connects to the steam line in the contracted region while the other end terminates in the upper part of the receptacle, the difference of level between the spiral and the receptacle being to the difference of level between the upper end of the oil pipe and the receptacle, as the specific gravity of oil is to water.

6. In an oiling system, in combination with a steam line, a receptacle adapted to contain oil and a pair of pipes connected to the steam line at points where the pressures are different and ending in the receptacle, the pipe connected to the point of higher

pressure ending in the upper part of the receptacle and serving to condense steam so as to establish a water column therein.

7. In an oiling system, in combination with a steam line, a receptacle adapted to contain oil and a pair of pipes connected to the steam line at points where the pressures are different and ending in the receptacle, the pipe connected to the point of higher pressure having a condenser between its ends.

25 In testimony whereof I have hereunto set my hand.

DIRK JAN CHRISTIAAN MEYERINGH.
